UNITED STATES PATENT OFFICE.

FRANK O. MITTAG, OF PARK RIDGE, NEW JERSEY.

BOAT.

1,307,873.

Specification of Letters Patent.

Patented June 24, 1919.

Application filed May 1, 1919. Serial No. 293,983.

To all whom it may concern:

Be it known that I, FRANK O. MITTAG, a citizen of the United States, and a resident of Park Ridge, in the county of Bergen and State of New Jersey, have invented certain new and useful Improvements in Boats, of which the following is a specification.

The invention resides in a novel type and 10 construction of boat to be driven by power.

One object of the invention is to provide a high-speed boat which will ride steadily through and to a large extent on or over the 15 surface of the water and have no tendency to turn over.

The boat of my invention has a hull which is comparatively wide and long and formed with a bottom which is longitudinally concaved from bow to stern and with sides 20 which are substantially parallel from the bow to the stern of the boat and are characterized by being concavely curved from their upper to their lower edges. The lower portions of the sides of the boat extend outwardly beyond the vertical plane of the 25 upper edges of said sides, and the lower edges of said sides and the side edges of the bottom of the boat meet one another at a sharp angle, the bottom of the boat extending directly upwardly and inwardly 30 from the lower edges of said sides and said sides curving upwardly and inwardly from the said side edges of said bottom. My boat when viewed from above presents substantially an oblong outline as distinguished 35 from high speed boats having convexly curved sides converging at their forward portions to form a sharp-pointed bow.

My boat is of staunch construction, and 40 this construction with other details and advantages of my invention not hereinbefore enumerated, will be fully understood from the specific description hereinafter presented with reference to the accompanying drawings, in which:

Figure 1 is a side elevation of a boat constructed in accordance with and embodying my invention;

Fig. 2 is a top elevation of the same;

Fig. 3 is a bottom view of the same;

Fig. 4 is a vertical transverse section, on a larger scale, through the same taken on the dotted line 4-4 of Fig. 1;

Fig. 5 is a detached top view of a detail 55 of the construction shown in Fig. 4;

Fig. 6 is an end elevation of a portion

of the skeleton frame involved in the construction of the sides and bottom of the boat, and this view shows the side of said frame reversed to that presented in Fig. 4; 60

Fig. 7 is a detached perspective view of a portion of the same;

Fig. 8 is a side elevation, partly in section and partly broken away, of a portion of the framing of the boat, this view being 65 taken at one of the steps or risers in the bottom of the boat and the planking on the side of the hull being omitted, and

Fig. 9 is a detached perspective view, partly broken away, of the frame construc- 70 tion at said step or riser.

In the drawings, 10 designates the opposite sides of the boat, 11 the bow, 12 the bottom and 13 the stern, which, as shown in Fig. 2, is transverse and preferably 75 straight.

The bow portion of the boat is preferably covered over by a deck 14, in rear of which is provided a commodious compartment 15 for passengers, engines and equipment cus- 80 tomary to power-driven high-speed boats.

The forward edge of the bow 11 is deflected downwardly and forwardly at an angle, as shown at 16, and the side portions of this angular edge curve forwardly to 85 a slight extent, as at 17, while intermediate said portions 17 the said angular edge curves inwardly on a concave line, as at 18.

The construction of the sides of the boat and the formation of the bottom of the boat 90 with reference thereto, are features of special importance.

The sides 10 are substantially parallel from bow to stern and of concave outline in vertical cross-section throughout their 95 length, being projected outwardly along their lower portions beyond the vertical planes of the upper edges of said sides, as shown in Fig. 4.

The sides 10 are constructed with a series 100 of spaced-apart vertically disposed ribs 19, which curve inwardly to provide the correct shape for said sides and upon which the exterior side planking 20 (Fig. 4) is secured.

The ribs 19 are connected together and 105 braced adjacent their upper and lower portions by longitudinal beams 21 (Fig. 4), and adjacent to their lower ends the ribs 19 are connected with transverse beams 22 which extend across the boat, while at their 110 extreme lower ends said ribs are secured to upwardly and inwardly inclined braces 23,

whose upper ends are secured to said transverse beams 22. I preferably interpose blocks 24 directly below the ends of the cross-beams 22 and alongside of the ribs 19, 5 and the lower ends of these blocks are between said ribs 19 and the outer ends of the braces 23, as shown in Fig. 6, and are secured to said ribs and braces and increase the strength of the general structure. I also 10 preferably secure auxiliary brace-bars 25 against the braces 23, and these bars extend up to the lower edges of the cross-beams 22 and aid in supporting the same.

I further increase the strength of my boat 15 structure with the use of vertical bars 26 whose upper ends are rigidly secured to the inner faces of the ribs 19, whence said bars 26 extend downwardly and are secured to the cross-beams 22 and brace-bars 23, 25.

20 The foregoing description of the ribs 19, cross-bars 22, braces 23, auxiliary braces 25 and vertical rods 26 applies to those portions of the boat removed from steps or risers 27 which I provide in the bottom of the boat

25 and toward the stern thereof, and at the location of these steps or risers 27 I provide ribs and rods corresponding with the ribs 19 and rods 26, but by reason of their being differently associated with other features of the boat, I number said ribs 28 and

30 said rods connected with them as 29. At the location of the steps or risers 27 I arrange the side ribs of the boat in pairs, as indicated by dotted lines in Fig. 1 and solid lines in Figs. 8 and 9. The ribs 28 are concaved inwardly, the same as the ribs 19, and they extend downwardly to the bottom of the boat and are secured to a pair of transverse beams 30 which are concaved at their 35

40 lower sides, as at 31 (Fig. 9), and extend out to the lower outer side edges of the boat at the angle at which the sides and the bottom of the boat meet. The rods 29 are vertical and secured at their upper ends to the

45 ribs 28, while at their lower portions they are secured to the transverse beams 30, as will be clearly understood on reference to Figs. 8 and 9. The steps or risers 27 are not 50 separately claimed herein, because they are not new features in speed boats.

The bottom 12 of the boat is gently concaved upwardly on transverse lines, from the bow to the stern of the boat, as indicated by the dotted lines in Fig. 1 and by 55 solid lines in Fig. 4, and said bottom 12 is formed of longitudinal planking rigidly secured to the transverse braces 23, auxiliary brace bars 25, transverse or cross-beams 22 and beams 30, the cross-beams 22 being concaved, as represented in Figs. 4 and 6, and

60 the beams 30 being similarly concaved to present gradually concaving surfaces adapted to receive the planking of the bottom 12, which planking I number 32 in Fig. 4. The 65 bottom of the boat, especially at the upper

portion thereof, presents a continuous surface extending from the bow to the stern of the boat, as denoted by the dotted lines in Fig. 1, and said bottom at the opposite side edges of the boat at the steps or risers 27, 70 present non-continuous edges, as will be apparent on reference to Figs. 1 and 3. The forward portion of the bottom 12 inclines upwardly along the bow end of the boat, and at the rear of said upwardly curved 75 portion the bottom 12 extends on substantially flat longitudinal lines to the stern of the boat.

The compartment 15 is formed of substantially vertical sides and a flat bottom and is 80 composed of durable planking secured, at the sides of the compartment, to the ribs 19, rods 26, planking 21, ribs 28 and rods 29, while the planking for the flooring of the compartment 15 is secured upon the upper 85 edges of the cross-beams 22 and beams 30.

My boat as a whole has been designed to present a durable seaworthy construction and one capable of high-speed.

My invention will be largely understood 90 from the foregoing description so that further extended detailed explanation is not required. I may mention, however, that when the boat is in use and driven by high power, so as to create speed, the bow of the 95 boat rides upwardly in and over the water due to the construction of the bow portion of the boat and the bottom thereof, while the stern of the boat partly submerges. The special construction of the sides of the boat 100 in coöperation with the construction defined for the bottom of the boat, permits the attainment of high speed without danger of the boat turning over, and also assures easy, steady, safe-riding of the boat on and partly 105 in the water. The exterior shape of my boat and its bottom construction contribute to high efficiency so that the boat constructed as described may employ engines of high H. P.

Among the purposes I have accomplished 110 by my construction of boat, is the attainment of high speed, steady and safe riding and capability of short turning or deflection within limited space. My construction of boat also permits me to use engines of high 115 H. P. and to minimize friction and resistance, all this being true even though the boat of my invention is comparatively broad with blunt bow and stern portions, as distinguished from high speed boats having sharp 120 pointed bows and outwardly convexed sides and which otherwise lack the characteristics of my boat.

What I claim as my invention and desire to secure by Letters-Patent, is:

1. A boat of the character described having substantially parallel sides which are extended downwardly and outwardly along their lower portions from bow to stern, the lower edges of said sides being set outwardly 130

beyond the plane of the upper edge of said sides and meeting the bottom of the boat at an angle.

2. A boat of the character described having substantially parallel sides which are concaved inwardly on vertical planes from bow to stern and the lower edges of which sides join the bottom of the boat at an angle.

3. A boat of the character described having substantially parallel sides which are concaved inwardly on vertical planes from bow to stern and from their upper to their lower edges, and the lower portions of said sides being extended outwardly beyond the vertical plane of the upper edges of said sides.

4. A boat of the character described having substantially parallel sides from bow to stern and whose lower portions extend outwardly beyond the vertical plane of the upper edges of said sides, and a bottom which is concaved upwardly from bow to stern and meets the lower outwardly projecting members of said sides at an angle.

5. A boat of the character described, having substantially parallel sides from bow to stern, and a concave bottom, the boat structure comprising inwardly concaved side ribs, exterior planking secured thereto, depending rods secured to the inner faces of said ribs, transverse beams secured to said ribs and rods, upwardly inclined braces secured to the lower ends of said ribs and rods and to said cross-beams, and bottom planking secured to said braces and cross-beams and

joining the outer planking of said sides at an angle.

6. A boat of the character described having substantially parallel sides from bow to stern and whose lower portions turn outwardly beyond the vertical plane of the upper edges of said sides, and a bottom which is concaved upwardly from bow to stern and meets the lower outwardly projecting members of said sides at an angle and which bottom curves upwardly at its bow portion and in rear of said portion is formed at its edge portions with a plurality of risers or steps.

7. A boat of the character described having substantially parallel sides which are concaved inwardly on vertical planes from bow to stern, a forward or bow-line which extends downwardly and forwardly at an angle, and a transversely concaved bottom extending the length of the boat and joining the outwardly projecting lower edges of said sides at an angle, the forward portion of said sides and bottom being curved upwardly toward the bow-line of the boat and in rear of said portion being extended toward the stern of the boat on substantially flat longitudinal lines.

Signed at New York city, in the county of New York and State of New York, this 23rd day of April, A. D. 1919.

FRANK O. MITTAG.
